UNITED STATES PATENT OFFICE.

GUSTAVE LEOPOLD MILLER, OF GENESEO, ILLINOIS.

CORN-HUSKER.

1,250,613.

Specification of Letters Patent. Patented Dec. 18, 1917.

Application filed December 27, 1916. Serial No. 139,094.

To all whom it may concern:

Be it known that I, GUSTAVE L. MILLER, a citizen of the United States, and a resident of Geneseo, in the county of Henry and State of Illinois, have invented certain new and useful Improvements in Corn-Huskers, of which the following is a specification.

My invention is an improvement in corn huskers and has for its object to provide a device of the character specified, wherein a plate is provided curved in such manner as to conform approximately to the shape of the ear, and arranged within the fingers, the palm, and over the ball of the thumb, and having means for assisting in the firm grasp of the ear, and wherein the fingers and thumb are left free.

In the drawings,

Fig. 1 is a perspective view showing the manner of grasping the ear to break it from the stalk,

Fig. 2 is a front view,

Fig. 3 is a rear view of the husker detached,

Figs. 4 and 5 are sections on the line 4—4 and 5—5 of Fig. 2, and

Fig. 6 is a front view of a modified construction of husker.

In the embodiment of the invention shown in Figs. 1 to 5, a support 1 of leather or the like is provided, of sufficient size to cover the palm of the hand, and straps 2 and 3 are provided for securing the support on the hand of the user.

The strap 2 has one end permanently connected to the support at one side thereof, and the other end is adapted to engage a buckle 4 which is secured to the opposite side edge of the support. A tab 5 is permanently connected with the same side of the support as the strap 1, and the said tab carries a buckle 6 at its free end for engagement by the strap 3. A plate 7 of rigid material, as for instance metal, is secured to the support, by means of rivets or the like, and the said plate is curved to fit within the palm of the hand from approximately the second joint of the fingers to and over the ball of the thumb. The outer end of the plate is of a width to extend from the inner side of the first finger, to and beyond the little finger, and the plate has an extension 8 at the outer side of the hand which curves around the said outer side, as shown more particularly in Figs. 1 and 2. An arm or

extension 9 is connected to the opposite side of the plate at approximately the center thereof and at such position that when the husker is in place on the hand, this arm or extension will extend between the thumb and the forefinger.

The strap 3 before mentioned, has one end permanently connected with the outer end of this arm by means of a rivet as indicated at 10, and the said strap passes across to the opposite side of the support and through a loop 11 secured to the said opposite side by means of a tab 12, and then back across to the opposite side of the support to a buckle 6 before mentioned.

It will be noticed that that portion of the plate between the first joint of the forefinger and the thumb, is cut away as shown at 12 to permit full freedom of the thumb, and that portion of the plate at the palm of the hand, and just in front of the base of the thumb is roughened to assist in grasping the ear, the roughening being provided in the present instance by spurs 13 which are struck up from the material of the plate. These spurs point toward the outer ends of the fingers, and a husking hook 14 is arranged on the plate at the ball of the thumb and on the inner side of the series 85 of spurs, the said hook being secured to the plate by means of rivets or the like 15, and it will be noted that the bill of the hook is bent parallel toward the plate.

This hook consists of three portions, 90 namely, that portion which is secured to the plate, the bill of the hook and the connecting portion between the bill and the first named portion, and it will be observed that the angles between the attached portion, the bill and the connecting portion, are at approximately right angles to avoid catching of the husk between the bill and the attached portion. That portion of the plate beyond the curved portion 8 may be 95 integral with the plate, or the said portion may be adjustable, as shown in Fig. 6, wherein this portion 7^a is connected to the body of the plate by screw bolts 16.

Each bolt engages an opening in the body 105 of the plate 7, and one of the series of openings in the portion 7^a, so that the portion 7^a may be adjusted with respect to the portion 7 to fit various sized hands.

In use, the husk is torn loose with the 110 hook, and the operator grasps the ear in the manner shown in Fig. 1, sliding the

hand toward the butt of the ear, while the left hand grasps the stalk, spreading the husk. The ear is now bent upward as indicated by the arrow in Fig. 2, breaking it 5 from the stalk and from the husk which remains with the stalk. The thumb and fingers merely aid in holding the ear which is broken or torn from the stalk, not by the thumb and fingers, but by the plate. It is 10 through the operation of the device, that is the husker, and not through the use of the thumb and fingers, that the ear is broken from the stalk. That portion beyond the extension 8 is so shaped that a part of all 15 the fingers and the greater part of the first and second fingers, extend beyond the plate. This permits the ear of corn to be firmly grasped, and the plate extending over the ball of the thumb relieves the fingers from 20 any strain in the breaking or snapping of the ear from the stalk.

The spurs 13, which in the present instance are nine in number, are for the purpose of permitting the ear to be very firmly 25 grasped during the breaking from the stalk. The bill of the hook points inward toward the plate to avoid striking and breaking out the kernels of corn. It will be noticed that the arm 9 is reinforced by bending 30 the same on its longitudinal axis to provide for an angular portion between its ends.

The curved arm 9 fits smoothly but closely over the hand, between the thumb 35 and fore-finger, to securely anchor the plate 12 on the hand, and prevent lateral swinging movement of the plate in any direction. This plate is of special advantage during 40 the snapping of the ear.

40 I claim:

1. A device of the character specified comprising a flexible support having means for connecting the same to the hand and a rigid plate secured thereto extending from approximately 45 the outer side of the base of the thumb to the second joint of the fingers, and curved to fit over the base of the thumb and in the palm of the hand, and to permit the fingers to move into grasping position, said plate having a rigid arm curved over the edge of the hand between the thumb and the forefinger, and having an extension curved over the outer edge of 50 the hand.

55 2. A device of the character specified comprising a flexible support having means for

connecting the same to the hand and a rigid plate secured thereto extending from approximately the outer side of the base of the thumb to the second joint of the fingers, 60 and curved to fit over the base of the thumb and in the palm of the hand, and to permit the fingers to move into grasping position, said plate having a rigid arm curved over the edge of the hand between the thumb and 65 the forefinger.

3. A device of the character specified comprising a flexible support having means for connecting the same to the hand and a rigid plate secured thereto extending from approximately 70 the outer side of the base of the thumb to the second joint of the fingers, and curved to fit over the base of the thumb and in the palm of the hand, and to permit the fingers to move into grasping position. 75

4. A device of the character specified comprising a rigid plate consisting of a body portion extending from the base of the thumb to the connection of the fingers with the hand and a curved extension at the end 80 adjacent to the fingers and shaped to permit the fingers to be curved to grasp an ear of corn, said extension extending to approximately the last joint of the fingers when they are curved over the same, and 85 means for securing the plate to the hand.

5. A device of the character specified comprising a rigid plate having a length corresponding to the length of the hand and shaped to fit within the hand when partially closed, as in grasping position, the said plate consisting of sections adjustable with respect to each other, and having means for securing them in adjusted position, said plate being of a width at its 95 outer end to extend from the inner side of the index finger to the inner side of the hand and being cut away at the thumb to permit the index finger and thumb to grasp an ear of corn. 100

6. A device of the character specified comprising a rigid plate having a length corresponding to the length of the hand and shaped to fit within the hand when partially closed, as in grasping position, said 105 plate being of a width at its outer end to extend from the inner side of the index finger to the inner side of the hand and being cut away at the thumb to permit the index finger and thumb to grasp an ear 110 of corn.

GUSTAVE LEOPOLD MILLER.
